UNITED STATES PATENT OFFICE

2,086,956

PAINT SPREADER

Frank L. Long, Des Moines, Iowa

Application November 15, 1933, Serial No. 698,105

4 Claims. (Cl. 15—231)

The object of my invention is to provide a paint spreader for wire screens of simple, durable and inexpensive construction, and by the use of which the wire screen of a screen door or the like may be painted rapidly and the paint distributed smoothly and evenly over the entire surface of every wire without smearing paint upon the adjacent portion of the door frame.

A further object is to provide a device of this character comprising a body and a detachable handle so constructed that when the handle is applied to the body, the paint absorbent fabric will be tightly stretched and firmly held in position, but may be removed and replaced by simply removing the handle.

My invention consists in the construction, arrangement and combination of the various parts of the device, whereby the objects contemplated are attained, as hereinafter more fully set forth, pointed out in my claims, and illustrated in the accompanying drawing, in which:

Figure 1 shows a perspective view of a complete device embodying my invention.

Figure 2 shows an enlarged, detail, sectional view through one of the side edges thereof.

Figure 3 shows a perspective view of the bottom plate and the end members connected therewith.

Referring to the accompanying drawing, I have used the reference numeral 10 to indicate the body portion of my improved paint spreader, which is preferably made of spring metal and comprises a top portion 11 having side members 12 and end portions 13. The side members are first bent downwardly and inwardly and thence downwardly and outwardly, terminating in vertical side portions 14, the lower edges of which terminate in horizontal inwardly extending portions or flanges 15, in the manner clearly illustrated in Figures 1 and 2.

The end members 13 are formed integral with the top 11 and bent downwardly over the upper portions of the ends of the members 12, thus providing openings 16 below the lower edges of the members 13. The portions 14 and 15, together with the lower edges of the members 12, provide internal grooves 17 for supporting the side edges of a bottom member 18, which is also preferably made of sheet metal and formed comparatively flat. Each end of the bottom 18 is provided with upwardly extending end members 19 designed to fit in the openings 16 for closing the same when the bottom member is in operative position.

The end members 13 strengthen and brace the main body 10, so that only the sides 12 spring

outwardly to yieldingly receive the plate 18, and the fabric 17, so that light sheet metal may be used. The upturned end members 19 of the plates 18 brace said plate against bending upwardly at the longitudinal center by pressure applied to the body against a screen.

Supported adjacent to the under surface of the bottom member 18 I have provided a paint absorbent fabric 20 of a somewhat greater width than the width of the plate 18, and having its side edges rolled upwardly and inwardly over the side edges of the bottom member 18. The said fabric is placed in position with the member 18 removed from the body 10. The bottom member, together with the fabric, may be placed in position by sliding the bottom member and said fabric longitudinally through the openings 16, with the side edges of the fabric resting on the flanges 15.

On account of the body 10 being formed of 20 spring sheet metal, it will be seen that the fabric will be firmly held in position and yet may be easily removed if so desired.

The fabric best adapted for this purpose is provided with downwardly projecting bristles 21. I find that a piece of carpet material works very satisfactorily for the paint absorbent fabric.

The flange 15 is of such width as to permit the outer edges of the outside longitudinal rows of bristles to barely touch the frame member 22 supporting the screen wire 23 being painted. The member 14 limits the movement of the spreader toward said frame, whereby the screen may be painted without painting the inner face of the frame member 22.

Thus means is provided whereby the screen may be painted without painting the frame member 22. This is of particular advantage when it is desired to paint the screen a different color from the frame, thus enabling the operator to rapidly paint the screen without danger of smearing paint over the inner faces of the frame members.

In the operation of my device, the bristles or nap of the fabric may be dipped in the paint, or the paint may be applied to said bristles by means of a suitable paint brush, after which the same is applied to the screen by moving the spreader over the screen surface, the nap or bristles tending to force the paint evenly over the wire surfaces and prevent the filling in of the openings, thus eliminating the difficulty usually experienced in painting screens with an ordinary paint brush, wherein the openings usually become filled with the paint, unless extreme care is exercised in the application of the paint. By my improvement this

filling in of the paint is entirely eliminated and the work can be done very rapidly, and at the same time making a perfect job of painting.

It will readily be seen that the fabric used in connection with the paint spreader is comparatively cheap, and that in practice it is desirable to replace the fabric after it is worn. For that reason it is desirable to have means whereby the fabric may be easily and quickly replaced. This is accomplished by my improved construction.

I claim as my invention:

1. A paint spreader for wire screens, formed of spring sheet metal and comprising a side member depending from each of its side edges, said side member being first bent inwardly and downwardly and thence outwardly and downwardly, the lower edge of said side member terminating in an inwardly extending flange to form a longitudinal groove, end members fixed to the said side members to brace them, a flat sheet metal bottom member having upturned bracing ends, a paint absorbent fabric supported adjacent to the bottom surface of said bottom and having its side edges folded upwardly and inwardly over the side edges of said bottom member, said bottom member and folded portions being mounted in said longitudinal grooves.
2. A paint spreader for wire screens formed of spring sheet metal and comprising a side member depending from each of its side edges, said side member being first bent inwardly and downwardly and thence outwardly and downwardly, the lower edge of said side member terminating in a downwardly extending portion and thence in an inwardly extending flange to form a longitudinal groove, a flat sheet metal bottom member, a paint absorbent fabric supported adjacent to the bottom surface of said bottom having its side edges folded upwardly and inwardly over the side edges of said bottom plate, said folded portions being mounted in said longitudinal grooves.

3. A paint spreader for wire screens formed of spring sheet metal and comprising a body having downwardly extending side members, the lower edges of said side members being formed to provide internal longitudinal grooves; a flat sheet metal bottom member; a paint absorbent fabric supported adjacent to the bottom surface of said bottom member, having its edges folded upwardly and inwardly over the side edges of said bottom member and supported in said longitudinal grooves, said fabric having a row of downwardly and outwardly extending bristles along each of its side edges, the outer edges of each row of bristles terminating in vertical planes common to the outer surface of the lower edges of said side members, whereby the lower edges of said side members serve as guides to prevent the bristles from engaging adjacent sides of the frame supporting the wire being painted.

4. A liquid spreader comprising a handle member formed of spring sheet metal having downwardly extended side members, the lower edges of said side members being extended first outwardly and then inwardly toward each other to form longitudinal grooves, a flat sheet metal bottom member, a liquid absorbent fabric extended across the bottom surface of said bottom member with its side edges folded upwardly and inwardly over the bottom member, said bottom member and the edges of said fabric being inserted in said longitudinal grooves and yieldingly held in position by the resiliency of the spring metal side members, said fabric having bristles projecting from one side thereof, the bristles at the side edges of the fabric being covered by said inwardly extended side edges of the handle member throughout the entire length of the fabric.
